UNITED STATES PATENT OFFICE.

WALTER D. TUSTEN, OF NEW YORK, N. Y.

CHAIN-LINK.

1,037,086.

Specification of Letters Patent. Patented Aug. 27, 1912.

Application filed May 15, 1912. Serial No. 697,416.

To all whom it may concern:

Be it known that I, WALTER D. TUSTEN, a citizen of the United States, and a resident of the city of New York, borough of Brooklyn, in the county of Kings and State of New York, have invented a new and Improved Chain-Link, of which the following is a full, clear, and exact description.

My invention relates to an improvement in ornamental chains, and particularly to the construction of the links thereof, and it comprises certain improvements in the structure of the chain shown and described in my prior application Serial Number 669,295, filed January 3, 1912 and allowed April 16, 1912.

Reference is to be had to the accompanying drawings forming a part of this specification, in which the same characters of reference indicate the same parts in all the views.

Figure 1 is a front elevation of a chain intended to be worn on the arm, made in accordance with my invention; Fig. 2 is a longitudinal section view of one of the extensible links of the same, the plane of section being vertical when the arm on which the chain is worn is in a horizontal position; Fig. 3 is a view similar to Fig. 2, showing the parts of the link in extended position; Fig. 4 is a longitudinal sectional view taken on a plane at right-angles to the plane of section of Figs. 2 and 3; Fig. 5 is a perspective view of one section of the extensible link shown in Figs. 3 and 4; and Fig. 6 is a perspective view of the other section of the above-mentioned extensible link.

My improved chain comprises a number of links made in sections movable with respect to each other to permit the chain to be distended whenever desired; as, for instance, to permit the length of the chain to be increased when it is to be used in the form of a bracelet or armlet, so as to enable it to be slipped over the hand into position.

In the form shown in Fig. 1, the numeral 1 indicates a number of solid links or gem settings carrying stones 2 held in place by means of cup-shaped flanges or rings 3, which are soldered to the settings 1. These

soldered links or settings alternate with the extensible links which are shown as having eyelets 4 at their opposite ends, these eyelets extending into the members 1 and engaging projections on the interior of the same in a manner that need not here be described, so as to cause all of the links to be movably connected together.

The numeral 5 indicates a watch or other ornament which is secured to the ends of the chain; and when the chain is to be put on the wrist it is merely slipped over the hand. The sections of the extensible links give to the required extent, and after being put in place the chain contracts and embraces the arm or wrist firmly, so as to remain in position thereon.

The extensible links which carry the eyelets 4 each comprises a box-like section 6 having open sides and closed ends 7. One of these ends carries an eyelet 4, and the other end is recessed at its sides, as shown at 8, and from the inner face of this recessed side projects a shank 9. This shank 9 serves to receive a spiral spring 10 which forms the means for making the link extensible, so as to enable the chain to be lengthened or shortened. This hollow box-like section 6 is received between the arms of a U-shaped section comprising a base 11 and arms 12. These arms 12 have perforations 13 in their outer ends, and through these perforations and the open sides of the box-like section 6 passes a pin 14. One end of the spring 10 which is located inside of the section 6, abuts against the pin 14, and a considerable portion of the length of this spring surrounds the shank 9 and abuts against the notched side 7, to which the shank 9 is secured. The shank 9 therefore serves as a sort of base or guide for the spring 10, and it also serves the purpose of a stop for the pin 14, limiting the relative movement of the sections of the extensible link, the parts being so designed that the end of the shank 9 will engage the pin 14 to prevent further movement of the sections before the spring 10 is compressed to such an extent as to be solid. In this way I avoid overcompressing the spring 10, and thus make it last much

90

100

longer in chains of this sort before its resiliency becomes sensibly diminished.

On the inner surface of the arms 12 of the U-shaped links are arranged longitudinally-extending projections in the form of ribs 15. These ribs are preferably two in number, and they are formed by stamping the metal of which the U-shaped section is composed, thus making corresponding longitudinal depressions or grooves 16 on the outer faces of the arms 12. The distance between the opposite edges of these ribs is equal to the width of the notches or recesses 8; and when the box-like section 6 is fitted 15 to the U-shaped section the notches 8 and the ribs 15 come into engagement with each other, the inner end of the section 6 thus has a sliding fit with the arms of the U-shaped section which receives it. The sections of 20 each extensible link therefore engage each other at two separated points on each side of the same, one of these points being marked by the pin 14 and the other of these points being marked by the location of the 25 notch 8 in the inner end of the section 6, and thus any tendency of the U-shaped section to rotate about the pin 14 as an axis, or of the hollow box-like section 6 to rotate about an axis, is entirely eliminated. Therefore, 30 the two sections of my extensible link are at all times kept in substantial alinement with each other in all relative positions of the two sections composing the same.

From the above description it will appear 35 that I have produced a superior article of the kind described, comprising means for limiting the relative movement of the sections of which the extensible links are composed, and guiding the resilient means by 40 which the links are controlled. The means for limiting the movement and guiding the resilient means in question comprises essentially the shank 9, which prevents the spring 10 from becoming compressed to such 45 an extent as to be made solid, this shank 9 also serving as a sort of guide for the spring and preventing it from flexing or curving when the links are extended and the spring compressed by forcing the ends thereof toward 50 each other. Furthermore, the longitudinally-arranged ribs on the inner faces of the arms 12 of the U-shaped section of the links has a sliding engagement, as above noted, with the inner ends of the box-like 55 sections 6, and these ribs coöperate with the pin 14, serving in a very efficient way to maintain the alinement of the sections when the links comprising the springs 10 are extended or contracted in practice. Further- 60 more, all of the working parts of the links are completely inclosed, and are thus protected from dust and dirt and any likelihood of injury.

I wish to have it understood that the

drawings and description of my invention 6 are illustrative only, and I do not care to be limited to the exact details of construction shown, except in so far as is indicated in the accompanying claims; and I also desire to have it understood that while my chain is 7 designed mainly for ornamental use, it is 7 by no means limited to such uses, as will be readily perceived.

Having thus described my invention, I claim as new and desire to secure by Letters 7 Patent:

1. In a link of the kind described, the combination of a pair of extensible sections, means carried by one of said sections for engaging the other section, resilient means 80 for engaging said sections to permit the same to have relative movement, and one or more longitudinally-arranged ribs carried by the first-named section, said second section having a notch to receive said ribs in 85 sliding engagement in position to clear said resilient means, said ribs and said first-named means serving to keep the said sections at all times in alinement with each other. 90

2. In a link of the kind described, the combination of a U-shaped section, a hollow box-like section having open sides received between the arms of said U-shaped section, the inner end of said box-like section having 95 recesses in its opposite lateral edges, a pin mounted in the ends of the arms of the U-shaped section passing through the other section, resilient means engaging said pin and the recessed end of the box-like section 100 to permit the said sections to have relative movement, and one or more longitudinally-extending ribs arranged on the inner faces of the arms of the U-shaped section and having a sliding fit with the notches in the 105 inner end of the box-like section, whereby the said sections will be retained at all times in substantial alinement. 110

3. In a link of the kind described, the combination of a pair of extensible sections, 110 a pin carried by one of said sections and engaging the other section, a longitudinally-extending shank carried by the other section against which said pin abuts to limit the movement of said sections, and resilient 115 means carried by said other section and surrounding said shank, said means abutting against said pin at one end and against the end of the other section at its opposite end. 120

4. In a link of the kind described, the 120 combination of a U-shaped section, a hollow box-like section having open sides received between the arms of the U-shaped section, an internal shank carried by the box-like section and projecting from the inner end 125 thereof, a pin carried by the U-shaped section and extending through the box-like section, and a spiral spring located inside of

the box-like section and surrounding said shank, said spring abutting against the inner end of the box-like section at one end and against said pin at the other, and said shank and pin serving to limit the relative movement of said section and prevent over-compression of said spring.

In testimony whereof I have signed my name to this specification in the presence of two subscribing witnesses.
